United States Patent Office

Des. 213,826

Patented Apr. 15, 1969

213,826

CHAIR

Alex Strassle, 9533 Kirchberg, St. Gall, Switzerland

Original design application Aug. 15, 1967, Ser. No. 8,274. Divided and this application May 7, 1968, Ser. No. 11,819

Term of patent 14 years

Int. Cl. D6—01

U.S. Cl. D15—1

Fig. 1

Fig. 2

Fig. 3

Fig. 4

Fig. 5

FIG. 1 is a front elevational view of a chair showing my new design;

FIG. 2 is a side elevational view thereof;

FIG. 3 is a rear elevational view thereof;

FIG. 4 is a plan view; and

FIG. 5 is an underside view thereof.

This is a division of my copending application, Ser. No. D. 8,274, filed Aug. 15, 1967.

I claim:

The ornamental design for a chair, substantially as shown.
